UNITED STATES PATENT OFFICE.

ALEXANDER GILCHRIST HAWES, OF LAS DELICIAS, CUBA

SUGAR-CANE MILL.

1,169,149.

Specification of Letters Patent. Patented Jan. 25, 1916.

Application filed January 29, 1915. Serial No. 5,029.

To all whom it may concern:

Be it known that I, ALEXANDER G. HAWES, a citizen of the United States, residing at Las Delicias, Province of Oriente, Cuba, 5 have invented certain new and useful Improvements in Sugar-Cane Mills; and I do hereby declare the following to be a full, clear, and exact description of the invention, such as will enable others skilled in the art 10 to which it appertains to make and use the same.

The invention relates to sugar-cane mills of the type employing three rolls in triangular arrangement, to wit, a lower feed roll, 15 a lower discharge roll and an upper pressure roll coöperating with the two lower rolls to crush the cane and extract the juice therefrom. In mills of this character, it has been customary to provide one or more of 20 the rolls with adjustable pressure devices, to regulate the pressure imposed upon the cane passing through the mill, and also to permit one of the rolls, usually the upper roll, to have a certain amount of movement relative 25 to the other rolls in order to accommodate the different characters and conditions of the cane fed to the mill. According to the generally accepted sugar-mill practice, the adjustable pressure-applying devices take 30 the form of hydraulic jacks associated with the journal bearings of one or more of the rolls and mounted in the frame of the mill to permit the roll or rolls thus provided to move away from the other rolls when a 35 heavy feed of cane is delivered.

In order to secure the best results from a sugar-cane mill, it is desirable that the pressures imposed between the feed roll and the top roll on the one hand, and the discharge 40 roll and the top roll on the other, be maintained constant and in a certain predetermined relation. This has not been possible of realization, however, with any of the various types of mills heretofore in use, for the 45 reason that the movement of any one or more of the rolls in a rectilinear direction against the imposed pressure produced by the coöperating hydraulic jacks inevitably resulted in a distinct change or variation in 50 the relation of the pressures between the upper roll and the feed and discharge rolls respectively.

The object of the present invention is to provide a mill in which a predetermined

relation of pressures between the top roll 55 and the two bottom rolls is maintained constant for all conditions of feed, but which may be varied at the will of the operator to suit any particular condition of feed. To this end, the invention contemplates the provision in a three roller mill of regulable means, such as hydraulic jacks, for imposing compound pressure on the upper roll, the resultant of which pressure is constant as to direction and intensity for varying conditions of feed, and to permit the proper application of such compound pressure and the necessary movement of the upper roll with respect to the feed roll and also the discharge roll, the upper roll is mounted in 70 journal bearings, carried by links which are pivotally connected to the shafts of the lower rolls, which links have mounted in their upper ends, the hydraulic jacks, adapted to impose differential predetermined 75 pressures on the upper roll, substantially normal to the axes of the upper roll and the feed roll and of the upper roll and the discharge roll respectively.

In the accompanying drawings: Figure 1 80 is a side elevation of a cane mill involving the invention, the driving gears of the rolls being omitted; and Fig. 2 is an elevation of the mill from the delivery side.

Referring to the drawings, 1 indicates a 85 bed-frame of suitable form and arrangement, upon which is journaled the feed roll 2, the discharge roll 3 and the upper roll 4 of a three-roll mill, each of said rolls being provided with shafts 2', 3' and 4', respectively, by which the rolls are driven, and which shafts are provided on each end with driving pinions, the gears 50, 50 on the lower rolls each meshing with gears 51, 51 on the upper roll, as illustrated in Fig. 2. 90 These gears may be operated in any suitable manner, preferably by a driving gear meshing with the gears of the lower rolls, at one side of the mill, in accordance with the usual 95 practice.

The discharge roll 3 is mounted in rigid bearings, consisting of lower and upper bearing blocks 5 and 6, which are rigidly secured to the bed plate 1 by anchor bolts 7 and cross yoke 8, at each side of the mill.

Feed roll 2 is preferably mounted in rocking bearings 32 located on each side of the mill and resting upon the upper face of the

100

105

bed plate 1, more particularly shown in Fig. 1.

The upper roll 4 is supported by its end journals 4' in two sets of links or struts 10 and 30, the pair of links 10 being pivotally connected to the shaft 3' of the discharge roller 3, and the pair of links 30 being connected at their lower ends with the rocking bearings 32, in which the shaft 2' of feed roller 2 is journaled, so that said links 30 are, therefore, pivotally connected to the shaft of the feed roll. Each link 10 comprises two longitudinal bolts 11 connected at their lower ends by a yoke 12, upon which is supported the lower journal bearing 14 engaging shaft 3'. The intermediate portion of the link 10 comprises an upper journal bearing 15, a filler piece 20, and a series of removable shims 21 interposed between the filler 20 and the upper bearing 15, to admit of the effective length of the link between the axes of the shafts 3 and 4 being adjusted, to thereby regulate the opening of the discharge pass of the mill between the upper roll 4 and the discharge roll 3. Above the filler 20 are located the two bearing members 16 and 17, which engage the shaft 4' of the upper roll, and interposed between the upper bearing 17 and the yoke 12', connecting the upper ends of the bolts 11, is a hydraulic jack 19 which may be connected as usual with a suitable accumulator, not shown. The yoke 12' is adjustably secured to the bolts 11 by means of nuts 13, so that said yoke 12' and the member of the hydraulic jack connected therewith may be adjusted longitudinally of the bolts 11.

Each of the links 30 consists of two longitudinal bolts 31, which are rigidly connected to the corresponding rocking bearing 32, as indicated in Fig. 1, and between said rods are mounted an upper bearing 34 engaging shaft 2', a series of removable shims 41, a filler piece 40, bearing blocks 36 and 37 engaging the shaft 4' of the upper roll, a hydraulic jack 39, connected with another accumulator, a yoke 32', and adjusting nuts 33. As thus constructed and arranged, it will be observed that the upper roll is mounted in swinging bearings and is capable of moving up and down to accommodate the varying feed of cane, said upper roll in effect floating above the feed and discharge rolls and being supported in the two sets of links 10 and 30, pivotally connected respectively to the shafts of the discharge roll 3 and the feed roll 2. The pressure imposed upon the upper roll by the two sets of hydraulic jacks 19 and 39, respectively, is exerted in the planes of the longitudinal axes of the supporting links 10 and 30, respectively, and, therefore, normal to the axes of the feed roll and the upper roll on the one hand, and of the discharge roll and the upper roll on the other, and whatever the pressure exerted by

the respective sets of jacks 19 and 39, the resultant of the two pressures will be constant both in direction and intensity, so that any given feed of cane passing through the mill will be subjected to uniform pressures on 70 both the feed and delivery sides of the mill. Each set of hydraulic jacks 19 and 39 is preferably connected with a separate accumulator, so that any desired difference of pressure may be imposed upon the respective 75 jacks and transmitted to the upper roll. By changing the pressure on either set of hydraulic jacks, the resultant pressure of the top roll may be changed to bear heavier on either of the bottom rolls, or if desired, to 80 be evenly distributed between the two bottom rolls. This resultant pressure, when once determined, remains constant under all feeds of cane. If, for example, a pressure of 200 pounds per square inch is imposed on the 85 front jacks 39 and a pressure of 400 pounds per square inch on the back jacks 19, the resultant of these pressures will have a direction which will not change, but will remain constant whether the feed of the cane be 90 heavier or light, and the component pressures exerted between the upper roll and the feed roll on one hand, and the upper roll and the delivery roll on the other hand will remain constant, so that the cane will be fed 95 uniformly through the mill without tendency to choke and a maximum and uniform extraction of the juice will result.

As is well known, different grades of cane require different settings or adjustments of the feed and discharge passage as well as the pressures imposed between the rolls forming these passes. By appropriately changing or varying the relative pressures produced by the two sets of jacks 19 and 39, it may be readily effected by the removing or adding weights to the accumulators supplying the respective jacks, the resultant pressure on the top roll may be varied in direction and also in intensity, and these changes of adjustments may be effected while the mill is running, thereby allowing a change of setting of the mill to suit the variations in the cane to be ground. In order to adjust the setting of the top roll with respect to the feed and discharge rolls, to regulate the feed and discharge passes of the mill, the effective lengths of the links between the axes of the top roll and the feed roll and discharge roll, respectively, 105 may be varied by adding or removing the shims 21 and 41, respectively, and correspondingly adjusting the set nuts on the upper portions of the links 10 and 30. In order to take up any side thrust of the rollers and also to prevent any of the cane escaping laterally of the rolls, the roll 4 is 110 preferably provided with end flanges which overlie and engage the end faces of the feed and discharge rolls, as indicated. A re- 115

turner bar 45, of any suitable or desired type, may be applied between the feed and discharge rolls, as indicated in Fig. 1.

What I claim is:—

5 1. In a sugar-cane mill, the combination with the upper roll and two lower rolls, of regulable means for imposing compound pressure on the upper roll, the resultant of which pressure is constant as to direction and intensity for varying conditions of feed.

10 2. In a sugar-cane mill, the combination with the upper roll and two lower rolls, of regulable means for imposing two component pressures on the upper roll normal respectively to the axes of the upper and the two lower rolls, whereby the resultant pressure on said upper roll is maintained constant for varying conditions of feed.

15 3. In a sugar-cane mill, the combination with the upper roll and the two lower rolls, of links pivotally connected to the lower rolls and having journal bearings in which the upper roll is supported, and regulable means carried by each link for imposing pressure on the upper roll.

20 4. In a sugar-cane mill, the combination with the upper roll and the two lower rolls, of two pairs of links pivotally connected to the lower rolls and having journal bearings in which the upper roll is supported, and regulable means carried by each link for imposing pressure on the upper roll.

25 5. In a sugar-cane mill, the combination with the upper roll and the two lower rolls, of two pairs of links pivotally connected to the lower rolls and having journal bearings in which the upper roll is supported, and a regulable hydraulic jack carried by each link for imposing pressure on the upper roll.

30 6. In a sugar-cane mill, the combination with the upper roll and the two lower rolls, of two pairs of longitudinally adjustable links pivotally connected to the lower rolls and having journal bearings in which the upper roll is supported, and a regulable hydraulic jack carried by each link for imposing pressure on the upper roll.

35 7. In a sugar-cane mill, the combination of a lower feed roll having rocking journal bearings, a lower discharge roll having fixed journal bearings, two sets of links pivoted to opposite sides of the lower rolls and having journal bearings in which the upper roll is supported, and regulable hydraulic jacks carried by the upper end of each link for imposing pressure on the upper roll.

40 In testimony whereof I affix my signature, in presence of two witnesses.
